ELECTRICAL CONNECTER

Harold H. Rudd, Greensburg, Pa., assignor to
 Railway & Industrial Engineering Co., Greens-
 burg, Pa., a corporation of Pennsylvania

Application March 21, 1934, Serial No. 716,701

12 Claims. (Cl. 173—273)

This invention relates to electrical connectors and more particularly to connectors of the type commonly known as live line clamps.

Live line clamps may be employed for connecting any two conductors but are especially useful for connecting a tap line or branch to a live line or conductor without cutting the latter or otherwise interfering with current flow through the same.

An object of the invention is to provide a live line clamp of particularly simple, efficient and rugged construction which may be readily applied to a live line to obtain a reliable connection of a tap to the line. More particularly, an object is to provide a line clamp including a bolt having an overhanging lug or projecting head, a combined nut and ring member adapted to be threaded upon the bolt, and a clamp plate or connecting strip which serves as a guide for placing the clamp upon a line, the line being then clamped against the plate by turning the nut upon the bolt.

These and other objects and advantages of the invention will be apparent from the following specification when taken with the accompanying drawing, in which:

Fig. 1 is a side elevation, with parts in section, of one embodiment of the invention, the clamp being shown in place on a conducting line member;

Fig. 2 is a plan view of the same;

Fig. 3 is a fragmentary side elevation of the clamp;

Fig. 4 is a fragmentary side elevation of a modified construction; and

Fig. 5 is a side elevation of another form of the invention.

In the drawing, the reference numeral 1 identifies the threaded section of a bolt which has an elongated or non-circular head 2 projecting beyond one side of the axis of the bolt, the projecting portion of the head having an inclined face or clamping surface 3 directed towards said shank for engagement with a live line L. A nut 4 is threaded upon the shank 1 and has an integral ring member 5 for receiving the hooked end of an insulated switch puller or the like, not shown, by which the clamp may be applied to the live line. A clamp plate or connecting strip is reversely bent to provide approximately parallel portions 6, 7 which are each apertured to receive, respectively, the elongated head 2 and the threaded shank 1 of the bolt, and the intermediate portion 7 is continued as or merges into an extension 8 through which a bolt 9 is passed to

clamp a tap wire T to the connecting strip. The general form of the clamp plate, as viewed in side elevation, is U-shaped, with the inner leg 7 merging into the extension 8 that flares away from the outer leg 6 of the clamping section. 5 The washer 10 which bears against the tap wire preferably has a radial extension 11 which is engaged in a notch in the end of the connecting strip.

As best shown in Fig. 3, the portion 7 of the 10 clamp plate is preferably of non-uniform cross-section to provide a wedging surface 12 which is inclined towards the lower face 3 of the bolt head to force the line conductor L towards the shank of the bolt. Whether or not the inclined 15 surface 12 is provided on the clamping plate, the line conductor L will be forced against the bolt shank to produce a three point engagement of the clamp with the conductor. This necessarily results in a firm and low resistance contact engagement of the clamp with conductor 20 lines of different sizes.

It is particularly to be noted that a relatively small clearance is provided between the upper portion 6 of the clamping strip and the bolt head 25 2. The significance of this construction is that the clamping strip reinforces the bolt against bending when the clamp is applied to a conducting line and the forces thus exerted eccentrically of and transversely of the bolt tend to deflect 30 the head in a counterclockwise direction, as viewed in Fig. 1.

When the clamp is designed for use with line conductors of but one size, it is possible, as shown in Fig. 4, to provide the lower face of the bolt 35 head with a groove 3' and the upper surface of the clamp plate with a groove 12' for receiving the line L. It is usually preferable, however, to employ the inclined contact surfaces which provide a three point contact in place of the two 40 point contact which results when the clamping surfaces are grooved.

A simplified construction which may be quite satisfactory for some purposes is illustrated in Fig. 5. In this form of the invention, the combined ring and nut member 14 is threaded upon the bolt 15 which has a shank passing through both of the approximately parallel sections 16, 17 of a reversely bent clamp plate, the head of the bolt having a lug or extension 18 which engages in a corresponding non-circular aperture of the section 16 to prevent rotation of the bolt when the ring nut 14 is rotated. The portion 17 of the clamp plate is normally slightly concaved 50 upwardly to assist in wedging the line conductor 55

5 L against the shank of the bolt when the clamp is applied to a conductor. The free end of the section 16 of the clamp plate cooperates with the extension 18 of the plate to form a jaw or guide for facilitating the application of the clamp to a conductor.

10 The invention is not restricted to the particular constructions herein illustrated and described, as changes may be made in the design and relative disposition of the several parts without departing from the spirit of my invention as set forth in the following claims.

I claim:

- 15 1. A live line clamp comprising a clamp strip having a U-shaped clamping section with approximately parallel legs and a connecting section extending from the inner leg of the clamping section and flaring away from the outer leg to form a guide, means on the connecting section for establishing an electrical connection to a tap wire, and means for clamping against the inner leg of the clamping section a conductor on which the clamp is placed; said clamping means comprising a bolt having a shank extending 20 through the inner leg of the clamping section and a head section extending through the outer leg thereof, said head section having a non-circular portion engaged in a correspondingly shaped opening in the outer leg to prevent rotation of the bolt with respect to the clamp strip, and a nut threaded on said bolt to draw the head of the bolt towards said inner leg of the clamping section.
- 25 2. A live line clamp as claimed in claim 1 wherein in the non-circular portion of the bolt head section extends through the outer leg section to engage the conductor and clamp the same against said inner leg.
- 30 3. A live line clamp as claimed in claim 1 wherein in the head section includes a portion overlying the outer side of the outer leg section, whereby rotation of the nut on the shank forces the said leg sections towards each other to clamp the conductor.
- 35 4. A live line clamp as claimed in claim 1, wherein that surface of the inner leg which is directed towards the bolt head is inclined towards the bolt to force the conductor towards the bolt when clamping pressure is applied.
- 40 5. A live line clamp comprising a metal strip having a clamping section of an approximately U-shaped form with an extension integral with the inner leg of the clamping section and flaring away from the outer leg, said extension serving as a guide for facilitating the application of the clamping section to a conductor, means on said extension for establishing an electrical connection to a tap line, a bolt having a shank and a head extending respectively through the inner and outer legs of the clamping section, said head including a clamping portion positioned laterally of the shank and at the open side of the U-shaped clamping section of the metal strip, and a nut threaded on said shank for drawing the clamping portion of the bolt head and said inner leg towards each other.
- 45 6. A live line clamp as claimed in claim 5,

wherein the surface of said inner leg opposed to the clamping portion of said bolt head is inclined towards the shank of the bolt, thereby to wedge a conductor away from the open mouth of the U-shaped clamping section.

5 7. A live line clamp of the type including a metal strip having an intermediate section merging into two approximately parallel legs to form a U-shaped clamping section, a bolt extending through said legs and spaced from the outer ends thereof to provide an open jaw for receiving a conductor, and a nut threaded on said bolt for drawing the head of the bolt towards the clamping section leg at the opposite side of the jaw, characterized by the fact that said bolt has a 15 clamping portion located laterally of the bolt shank at the open jaw side of the clamping section, and the intermediate section of said metal strip lies adjacent and parallel to the bolt to reinforce the same against bending when clamp- 20 ing pressure is applied.

8. A live line clamp comprising a bolt having a threaded shank and a head having a clamping surface directed towards said shank, a clamp strip having reversely bent portions apertured to receive respectively said head and said shank, an extension on the portion of said strip through which said shank passes, means on said extension for clamping a tap wire thereto, and a nut threaded upon said shank for drawing said bolt head 30 against that portion of the clamp plate through which said shank passes, said clamping surface of said bolt head being inclined to the axis of the shank of said bolt to wedge a conductor laterally against the shank of said bolt.

35 9. A live line clamp as claimed in claim 8, wherein the clamping surface of said head is located at one side of the axis of said bolt, and the section of said clamp strip through which said bolt head passes has a substantially snug fit with 40 the opposite side of said bolt head to reinforce the bolt against bending.

10. A live line clamp comprising a bolt having a threaded shank and an elongated head extending laterally of said shank, a clamp plate having 45 an intermediate portion apertured to receive the said bolt shank, a reversely bent extension on said intermediate portion apertured to receive and reinforce the elongated head of said bolt, an extension at the opposite end of said intermediate portion and carrying means for connecting a wire thereto, and a nut threaded on said shank for forcing said intermediate section of said clamp plate towards the adjacent face of said elongated head.

55 11. A live line clamp as claimed in claim 10, wherein the opposed faces of said elongated head and said intermediate section of said clamp plate converge towards each other to wedge a conductor between the same and against the shank of 60 said bolt.

12. A live line clamp as claimed in claim 10, wherein the opposed faces of said elongated head and said intermediate portion of said clamp plate are grooved to receive a conductor.
